UNITED STATES PATENT OFFICE.

THEODOR SUCHLAND, OF BERLIN, ASSIGNOR TO VALENTIN LANDSBERG,
OF POSEN, GERMANY.

CHAIR.

SPECIFICATION forming part of Letters Patent No. 449,355, dated March 31, 1891.

Application filed August 27, 1888. Serial No. 283,887. (No model.) Patented in Germany February 10, 1888, No. 44,374.

To all whom it may concern:

Be it known that I, THEODOR SUCHLAND, of the city of Berlin, Prussia, Germany, have invented a certain new and useful Improved 5 Chair with Adjustable Seat, (a patent for which was granted to me in Germany, dated February 10, 1888, No. 44,374,) of which I declare the following to be a specification.

This invention relates to an improved chair 10 in which the seat is adjustable, so that the same can be raised or lowered, as may be desired, and will be securely held in any position by means of appropriate clamping-levers, which can be released from their engagement 15 with the vertical guide-rods by means of a knob or handle arranged so as to be readily operated on.

In the accompanying drawings, Figure 1 is 20 a vertical section of the chair, and Fig. 2 is a horizontal section of the same.

Vertical rods *a* are fixed in appropriate manner to the lower surface of the framework of the seat *h* or to the seat itself and arranged to slide up and down in suitable 25 tubes or guides *b*, preferably either fixed to or located within the legs of the said chair. The upper ends of the tubes *b* are either slotted or are screwed or fixed to suitably-formed shells or sleeves *c*, cut away at *c'*, so that the 30 case-hardened ends *d*² of the clamping-levers *d* can firmly bite on the rods *a*, fixed to the seat-frame *h*.

The clamping-levers *d* turn on the bolts *d'*, which run through the rail or rails *e* of strong 35 sheet or thin bar or single iron, the ends of which can be bent over to form the sleeves *c*, or the sleeves *c* can be made of a separate piece of metal and be screwed or otherwise attached to the rail or rails *e* or the frame of 40 the chair. The opposite ends of the clamping-levers *d* are carried by springs *f*, of helical form, and hung in the eyes *f'*; but flat springs can be used. I prefer, however, to employ helical springs, as the same are not so liable 45 to be ruptured as flat or leaf springs.

The clamping-levers *d* will allow the seat to be raised, but will allow no downward movement until the said levers are brought out of

engagement with the rods *a* by operating the knob or handle *i*.

As soon as the seat *h* has been raised to the desired height, the hardened tips *d*² of the levers *d* will securely bite on the rods *a*, and thus prevent all downward movement of the seat *h*, which is thus held in raised position, 55 so that the heavier the weight is on the seat the firmer will be the engagement of the ends *d*² of the clamping-levers *d* with the rods *a*.

In order to release the levers *d* from their engagement with the rods *a* and allow the 60 seat *h* to be lowered, I employ a *L*-formed bent rail *k*, the ends of which are arranged to turn on suitable hinges *l*. The forward end of the rail *k* is carried by a helical spring *o*, hung in an eye *o'*, said rail being, furthermore, provided with a knob or handle *i*. On each side of the rail *k* is a lug *m*, carrying a bolt *n* or its equivalent, which latter lies immediately above the rear ends of the clamp- 65 ing-levers *d* without in any way preventing 70 the lowering of the same.

If it is desired to lower the seat, the knob or handle *i*, and consequently the lugs *m* and rail *k*, are depressed until the bolts *n* or their equivalents come in contact with the rear 75 arms of the levers *d*, press the same downward, and release the tips *d*² from their engagement with the rods *a*, so that the said seat can be readily lowered. As soon as the knob or handle *i* is released the lever *k* will 80 be immediately raised by the spring *o* and the rear ends of the clamping-levers *d* by the springs *f*, so that the forward ends *d*² of the 85 said clamping-levers will be caused to immediately bite on and engage with the rods *a*.

What I claim as new, and desire to secure by Letters Patent, is—

1. In a vertically-adjustable chair-seat, the combination, with the seat and frame, the tubes *b*, the sleeves *c c'*, and the rods *a*, working therein, of the levers *d*, having the hardened sharp tips *d*² engaging with said rods by biting thereon, whereby the seat is held at the desired height, substantially as described.

2. In a vertically-adjustable chair-seat constructed as above described, the combination,

with the sliding rods *a* and levers *d*, engaging therewith, of the bent lever or hinged rail *k*, provided with the lug *m*, and bolt or stud *n*, engaging with the levers *d*, whereby the seat is lowered when desired, substantially as described.

In witness whereof I have hereunto signed

my name in the presence of two subscribing witnesses.

THEODOR SUCHLAND.
